Primary Examiner — Janice Hallmark*Assistant Examiner* — Elizabeth S Ko(74) *Attorney, Agent, or Firm* — Peter L. Brewer; Thrive IP(57) **CLAIM**

The ornamental design for a wedge block for a pipe support system, as shown and described.

DESCRIPTION

FIG. 1 is a perspective view of a wedge block for a pipe support system, showing my new design.

FIG. 2 is a second perspective view of the wedge block for a pipe support system of FIG. 1.

FIG. 3 is a front plan view thereof.

FIG. 4 is a rear plan view thereof.

FIG. 5 is a right side elevation view thereof.

FIG. 6 is a left side elevation view thereof.

FIG. 7 is a top plan view thereof; and,

FIG. 8 is a bottom plan view thereof.

The broken lines in the drawings depict portions of the wedge block for a pipe support system that form no part of the claimed design.

1 Claim, 4 Drawing Sheets(56)
